UNITED STATES PATENT OFFICE.

VIRGIL GRAZZINI, OF NEW YORK, N. Y.

DESIGN FOR A PICTURE-FRAME.

SPECIFICATION forming part of Design No. 36,924, dated May 24, 1904.

Application filed April 23, 1904. Serial No. 204,642. Term of patent 7 years.

To all whom it may concern:

Be it known that I, VIRGIL GRAZZINI, a citizen of the United States, and a resident of the city of New York, borough of Manhattan, in the county and State of New York, have invented a new, original, and ornamental Design for a Picture-Frame, reference being had to the accompanying drawing, which is a front view of a frame for pictures, mirrors, and the like, showing my new design.

I claim as new and desire to secure by Letters Patent—

The ornamental design for a picture-frame herein shown.

VIRGIL GRAZZINI.
